Primary Examiner — Melanie Pellegrini

(57) **CLAIM**

The ornamental design for a half-boot, as shown and described.

DESCRIPTION

1. Half-boot

1.1 : Perspective

1.2 : Front

1.3 : Back

1.4 : Right

1.5 : Left

1.6 : Top

1.7 : Bottom

The reproductions of the design show only the left shoe; the right shoe is omitted because it is symmetrical to the left shoe.
